MACHINE FOR REMOVING SHOES FROM
LASTS

William D. McKeon, Beverly, Mass., assignor to
United Shoe Machinery Corporation, Flemington, N. J., a corporation of New Jersey

Application October 11, 1947, Serial No. 779,396

8 Claims. (Cl. 12—15.1)

1

This invention relates to machines for effecting relative movement between shoes and their lasts and, more particularly, to machines of the type commonly referred to in the manufacture of shoes as "last-pulling machines." The invention is herein illustrated as embodied in a machine in which the requisite shoe-removing traction is imparted to a shoe-engaging element by a novel operating member.

Moving the rear portion of a shoe upper heightwise relatively to the last over which the shoe has been formed is ordinarily the most difficult step in last pulling. To accomplish such relative movement of the shoe, a machine must overcome progressive resistance due to the heightwise curvature of the last and to the very slight yieldability of upper leathers and fabrics without causing undue strain or marring. For an example of a last-pulling machine in which relative movement is performed by the operation of a shoe-engaging tool in the form of a driven concentric roll, reference may be had to United States Letters Patent No. 1,820,952 granted September 1, 1931, upon the application of John M. Whelton and Arthur F. Pym. Further reference may be had to United States Letters Patent No. 1,882,083, granted October 11, 1932, upon the application of G. A. Miner, in which a last-pulling machine is disclosed having in its organization flexible sheet material cooperating with a cylindrical roll to effect relative movement of a shoe and its last.

An object of this invention is to provide an improved machine which is simple in construction and operation for effecting the relative heightwise movement of the back portion of a shoe and its last.

In accordance with this object, one feature of the present invention resides in the provision of friction means, including a tool mounted for eccentric motion engageable with the rear portion of a shoe upper to move the shoe relatively to a last upon which the shoe is mounted. As shown herein, the eccentrically mounted tool is arranged to press an intermediate member progressively into engagement with the rear portion of each successively presented lasted shoe to move the shoe relatively to its last.

A further feature of the invention consists in the provision of means which assist the operator in properly presenting lasted shoes to the machine and then withdrawing them. With a single hand movement the lasted shoe may be guided against a gage where it is correctly positioned, regardless of shape or size, for engage-

2

ment with an eccentric roll and cooperating belt while the last is held upon a last-pin. Withdrawal from the roll and belt of the last and its shoe partially separated therefrom is then accomplished with the assistance of cooperating springs.

These and other features of the invention, including certain details of construction and combinations of parts, will now be more fully described in connection with the illustrative machine and pointed out in the claims.

Referring to the accompanying drawings,

Fig. 1 is a view in front elevation of an illustrative machine for separating shoes from their lasts in which the present invention is embodied;

Fig. 2 is a view in side elevation of the machine shown in Fig. 1;

Fig. 3 is a section on the line III—III of Fig. 1, the main frame of the machine being omitted and showing a conventional variable drive arrangement;

Fig. 4 is a vertical view of a shoe about to be worked upon and indicating the driven eccentric tool at one stage of operation, some of the parts being shown as sectioned on the line IV—IV of Fig. 1;

Fig. 5 is a view similar to Fig. 4, but illustrating the position of the tool at a subsequent stage of its operation on a lasted shoe;

Fig. 6 is a section on the line VI—VI of Fig. 1;

Fig. 7 is a plan view of the mechanism shown in Fig. 6;

Fig. 8 is a section on the line VIII—VIII of Fig. 6;

Fig. 9 is an enlarged view, in front elevation and partly in section on the line IX—IX of Fig. 10, showing details of the last-pin mounting and slide;

Fig. 10 is a section on the line X—X of Fig. 9;

Fig. 11 is a section on the line XI—XI of Fig. 40; and

Fig. 12 is an elevational view indicating accessibility of the eccentric roll and cooperating belt.

The illustrated machine has a hollow frame 10 (Figs. 1 and 2) which houses in its lower compartments driving mechanism later to be described. An eccentric roll bearing the general designation 23 (Figs. 4 and 5) comprises a metal hub 26 eccentrically mounted on an unsupported or outboard end portion of a horizontal shaft 32 having its opposite end portion journaled in bearing stands 34, 36 secured to the upper portion of the frame 10, and a resilient rubber annulus 25 which is bonded to the hub 26 and is substantially concentric therewith. For support-

ing the rubber annulus 25 against excess radial distortion due to operations which will hereinafter be described, retaining discs 27 partially cover both ends of the roll 23 and may be affixed to the hub 26. The roll 23 has its eccentric axis rearward of shoes to be operated on (Figs. 1 and 2) and is partly enclosed in a hood 11 secured to the frame 10. A shoe-engaging member in the form of a resilient endless belt 28, also preferably of rubber or rubber composition, is loosely suspended about the continuously driven eccentric roll 23 on horizontal idler rolls 30 which are supported within the hood 11. The belt 28 is periodically touched by the projecting surface of the eccentrically rotating annulus 25 to urge the belt intermittently over the rolls 30 at a rate dependent on the speed of the shaft 32, and these operative contacts between belt and roll occur in the locality of engagement between belt and shoe. The position of two of the idler rolls 30 situated adjacent to the back of the shoe is such as to provide for upward progress of the belt 28 and preferably along a path inclined slightly rearwardly from the vertical. A door 37 hinged to the hood 11 (see Fig. 12) is positioned at the unsupported end of the shaft 32 to permit ready access to the roll and the endless belt. This arrangement enables an operator conveniently to remove the belt 28 and to replace it in materials appropriate to the texture and color of the shoes in hand without the necessity for disassembly of the machine.

An upper portion of the frame 10 in the form of a shelf supports a boss 38 (Figs. 1 and 2). A hand wheel 40 which may be turned on thrust washers 42 of the boss 38 is in threaded engagement with a tubular jack 44. A bracket 50 for supporting the jack 44 is in the form of an upright cylindrical jacket having a tangential vertical plate through which bolts 49 extend to secure the bracket to the frame 10. An upper and a lower bushing 51 inserted in the bracket 50 engage the jack, the lower bushing 51 also engaging the upper end face of the hub of the hand wheel 40. A locking key 46 held stationary in the bracket 50 projects into a vertically extending keyway 48 of the jack 44 to prevent rotation of the latter as the hand wheel 40 is turned to raise or lower the jack.

A dovetailed guide-block 52 (see Figs. 9, 10 and 11) has a depending stem 45 which is inserted in the upper end of the jack 44, the block 52 being positioned centrally in front of the eccentric roll 23 (Fig. 1), and is prevented from turning on the jack by a pin 54. A slide 58 in dovetailed engagement with the guide-block 52 carries a last-pin 90 which is mounted in and extends upwardly from a barrel 60. A locking screw 62 secures the barrel 60 to the slide 58. A wearing piece 92 to be inserted into the thimbles of lasts, having a collar 64 for engaging the back cones of such lasts, fits over the upper end of the last-pin 90 and is locked to it by a tapered pin 68.

The lower portion of the barrel 60 is rectangular in cross section (Fig. 11) and a horizontal transverse slot 72 extends across its bottom (Fig. 10). A collar 70 is threaded into the bottom of the barrel 60 to hold a spring 66 (Fig. 9) in compression against the lower end of the wearing piece 92. The lower end of the last-pin 90 is enlarged beneath the collar 70 and is provided with ears 74 for engagement with the slot 72 to lock the last-pin 90 against rotary movement with respect to the barrel 60. This enlarged

lower end of the last-pin 90 is bifurcated to receive two S-shaped detents 78 fulcrumed on a pin 76.

The detents 78 are limited in counterclockwise movement about the pin 76 (Fig. 10) by their normal contact with the last-pin 90, while clockwise movement of the detents 78 is yieldably resisted by springs 82 which are retained by lugs 80 on the detents. Each detent 78 has a tooth 84 (Figs. 10 and 11) which is arranged to engage the teeth of a horizontal rack 86 upon slight depression of the last-pin 90, the teeth 84 being spaced apart longitudinally of the rack by a small length equivalent to half the thickness of a tooth in the rack 86. This offset of the teeth 84 with respect to the rack is such as to secure effective and fine adjustment in position of the last pin 90 along the rack. The teeth of the rack 86 are inclined to the right as viewed in Fig. 10. It will be apparent that in movement of the last-pin 90 toward the eccentrically mounted roll 23, even though the last-pin is depressed, the teeth 84 are permitted to travel over the teeth of the rack 86, whereas the slightly depressed last-pin may not be retracted from the roll 23 because of the register of one of the teeth 84 with a tooth of the rack 86, the tooth 84 being urged to register by its associated spring 82. If the spring 86 be permitted to raise the last-pin 90 slightly, however, the spring 82 cannot maintain engagement between its detent 78 and the rack 86, and the last-pin 90 will be moved away from the roll 23 by mechanism to be described below. The rack 86, it should be noted, is secured within the dovetailed block 52 by screws 88.

A pair of pins 56 extend down through the slide 58 and abut the ends respectively of a pair of compression springs 61 housed in horizontal parallel slots 53 in the dovetailed portion of the guide-block 52. The opposite ends of the springs 61 are held in the slots 53 by lugs 55 secured to the guide-block 52. Longitudinal movement of the last-pin 90 and the slide 58 over the rack 86 is, accordingly, yieldingly resisted in one direction by the compression of the springs 61. A gage-stand 94 (Figs. 6, 7 and 8) is mounted adjacent to a shoulder of the shaft 32, the latter being free to rotate in the gage-stand on a ball bearing 33 (Figs. 6 and 8). A collar 96 affixed to the shaft 32 prevents said gage-stand from sliding on the shaft. A stop 102 protruding from the base of the bearing stand 34 contacts the base of the gage-stand when no shoe is being operated upon and prevents any tendency of the gage-stand 94 to revolve in one direction about the shaft 32, due to operations which will hereinafter be explained, while any tendency of the gage-stand to revolve in an opposite direction is opposed by the resistance of a spring 98 (Fig. 6) vertically supported by an arm 100 affixed to the frame 10. The supporting shoulder 106 of a gage 104 is slidable in a slot 105 (Figs. 6 and 7) in the gage-stand 94 and an ear 108 is integral with the gage-stand 94. An adjusting screw 110, one end of which is held in the ear 108, extends through the internally threaded supporting shoulder 106 of the gage 104 and, upon rotation, adjustably moves the gage toward or away from the shaft 32 for purposes which will hereinafter appear.

A pin 112 (Figs. 1 and 2) commonly termed a "stripper" may be bolted on the upper shelf portion of the frame 10 and arranged to support

a last while the separation of a shoe therefrom is manually completed.

In the bottom compartment of the machine an electric motor 1 with its pulley 2 provides operating power and is suspended from a bracket 6 bolted to the frame 10. Mounted on the bracket 6 is a conventional variable drive arrangement having a housing 8 (Fig. 3) in which horizontal shafts 7 and 9 are journaled for carrying split V-type pulleys 3 and 5, respectively, and pulleys 13 and 12, respectively. Each of the pulleys 3 and 5 has a pair of conical flanges which are movable axially toward and from each other. A belt 22 (Figs. 1 and 2) from the motor pulley 2 drives the pulley 13. As the specific construction of the variable drive mechanism does not form a part of the present invention it is not described in detail. Pin 14 and 15 are located on suitable frame members (not shown) attached to the housing 8. These pins 14 and 15 serve as pivots about which a pair of arms 16 and 17, respectively, are arranged to fulcrum. With the arms 16 and 17 moving on their pivots, their corresponding and adjacent split pulley sections move accordingly, each section being connected to an arm by conventional construction. It suffices to state that each split pulley section of pulley 3 or 5 is provided with a flanged hub upon which a yoke is adapted to freely rotate. Each yoke has a pin which extends within a slot formed longitudinally of an arm 16 or 17. Right and left threads on a shifting screw 18 pass through and are in threaded engagement with shifting nuts each having a pin extending through a slot in the end of an arm 16 or 17 and, accordingly, turning of the screw 18 by the means of a hand wheel 20 on the outside of the housing 8 simultaneously positions the arms 16 and 17 on the shafts 7 and 9. For example, as the pivoted arms 16 and 17 are thus moved away from each other on the shaft 7, the conical sections of the pulley 3 are caused to separate from each other, while opposite ends of the arms 16 and 17 and the conical sections of the pulley 5 on shaft 9 are caused to move toward each other. As the two sections of a V-pulley separate, its V-belt will turn on a smaller effective diameter thereof. A V-type endless belt 24 connects the split pulleys 3 and 5, and a belt 19 conveys operating power from the pulley 12 to a pulley 35 mounted on shaft 32. Having adjusted the hand wheel 20 to provide a larger turning radius for the belt 24 on the pulley 5 and a smaller turning radius for the belt 24 as it passes over the pulley 3, it will be apparent that the rotative speed of shaft 9 will be less than that of shaft 7 and that consequently a lesser speed will be transmitted to the operating shaft 32 than is provided by the motor pulley 2.

In operation an inverted last L with a shoe S thereon is mounted on the wearing piece 92. The jack 44 carrying the wearing piece 92 has been adjusted vertically by turning of the hand wheel 40 to position properly the counter of the shoe heightwise of its locality of engagement with the gage 104 and the belt 28. The motor may be run continuously, always rotating the eccentric roll 23 in a clockwise direction, as viewed in Fig. 2. Speed of rotation of the mechanism including the eccentrically mounted roll 23 is regulated by the turning of the hand wheel 20 to accommodate the work capacity of the operator or to serve as his pacemaker, as well as to control the rate of operation at which progressive driving pressure and traction is to be applied to the shoe

by the belt 28. Adjusting the operating speed in this manner is particularly desirable in working on shoe uppers which may be of a large variety of leathers or fabrics to assure that traction imparted by the mechanism does not mar or unduly strain them.

The lasted shoe S mounted on the wearing piece 92 is moved by hand with the slide 58 over the guide-block 52 toward the axis of the eccentric roll 23 until its approach is limited by the back of the shoe or its heel contacting the gage 104, as indicated in Fig. 5. Previous setting of the screw 110 adjusts the position of the gage 104 so that successive shoes of any size and style are then properly located to be depressed while still in contact with the gage 104 and have their rearward portions properly presented for engagement with the belt 28. The gage 104 also serves to permit engagement of the shoe with the belt 28 only when the belt is pressed into such contact by the eccentric roll 23. It will be apparent that by reason of its eccentric mounting the roll 23 is sequentially engageable frictionally with the belt to drive the back portions of successive shoe uppers heightwise of their lasts. A slight depressing of the lasted shoe by hand causes the wearing piece 92 to compress the spring 66 and also results in one of the two detent teeth 84 engaging the rack 86 so as to hold the last and the shoe relatively to the eccentric roll in the position determined by the gage 104. During approximately the first half of the upward operating stroke of the roll progressively increasing pressure and traction due to its eccentricity are applied through the resilient annulus 25 and the belt 28 to the shoe. This is in accord with normal requirements since an increasing resistance must be overcome as the counter portion is moved over the curvature of the back of the last. The lateral thrust of the roll is prevented from displacing the last and shoe forwardly, however, due to the aforementioned detent and rack engagement and the operator is thereby enabled to maintain the shoe in frictional contact with the upwardly driving belt.

Normally, depressing a lasted shoe while maintaining its contact with the gage 104 is to be effected by the operator each time the eccentric roll 23 is about to swing into that portion of the belt 28 next to engage a shoe. Each upwardly swinging stroke of the eccentric roll 23 thus progressively presses successive portions of the resilient belt 28 into engagement with the rear portion of a shoe. While belt and shoe are in contact they partake of the upward driving action imparted frictionally by the resilient eccentric roll so as to be shifted upwardly relatively to the stationary last. Meanwhile, the upward swing of the gage 104 with its stand 94 is yieldingly resisted by the spring 98 until the shoe has separated from the gage 104 when the gage will return to its normal position and the gage-stand 94 will abut the stop 102. The shoe having been raised relatively to its last, the operator permits the spring 66 to raise the last-pin 90 and springs 82 cooperate to disengage the detent 78 from the rack 86. The springs 64 may then cause the wearing piece 92 carrying the last with its partially separated shoe to withdraw toward a position where they may be readily taken off the machine. It will be noted that treadle mechanism for accomplishing relative movement of the operating member and the lasted shoe is eliminated. Up to this point, the operator may have conveniently performed all 75 movements with his left hand alone. He may

now reach with his left hand for the next shoe to be operated upon while his right hand may utilize the "stripper" 112 completely to separate the shoe previously operated on from its last.

Successive shoes may be easily presented and conveniently held during movement from their lasts, the shoes being guided into consecutive operative engagements with the resilient belt just as the periodic upward motion and traction of the latter are about to be imparted by the eccentric roll. A proper speed reduction setting of the variable drive mechanism normally enables progressive portions of the outside belt surface and the opposite inner belt surface to come into engagement respectively with the shoes and the eccentric roll so as to almost entirely eliminate frictional marring of the shoes, and the effective wearing period of both eccentric roll and cooperating belt is thereby prolonged.

It will be understood that an eccentric tool may be arranged to progressively engage a lasted shoe to move the shoe relatively to its last without the cooperation of an intermediate member. The use of an intermediate member such as the belt 28 is preferred, however, to assure smoothness of operation and other advantages. Also, it will be appreciated that to obtain sequential shoe engagements the eccentric tool itself may take the form of a cam member having more than one projecting contact surface, although a tool in the form of an eccentric cam member having a single projecting contact surface, as shown in Figs. 4 and 5, is preferred.

By the words "lasted shoe," as used herein, is meant a shoe fitted over a last on which the shoe is being formed and constructed.

Having described the invention, what is claimed as new and desired to be secured by Letters Patent of the United States is:

1. A machine for operating on shoes comprising a support for a last with a shoe thereon, an intermediate resilient member arranged to be pressed against the rear portions of lasted shoes successively placed on said support, and a rotatable eccentric roll for intermittently and progressively pressing the member and simultaneously shifting the position of said member with the rear portions of said shoes relatively to their lasts.

2. A machine for operating on shoes comprising a support for a last with a shoe thereon, friction means engageable with the back portion of the lasted shoe upper, a driven eccentrically mounted roll included in said friction means, a slide for guiding the back of the lasted shoe on said support into operative position for engagement with said friction means, and positive means for maintaining the shoe in such position whereby the shoe is moved relatively to the last.

3. A machine for removing shoes from lasts, comprising frictional shoe-engaging means including an eccentrically mounted driven roll, a support for a last having a shoe thereon, said support being movable to a position wherein the back portion of the shoe is engageable by said means, a gage for limiting movement of the shoe toward the eccentric axis of said roll, and mechanism associated with said support for positively locking the last support in fixed position relatively to the eccentric axis of the roll, said shoe-engaging

means serving to move the back portion of the shoe relatively to the stationary last.

4. A machine for removing a shoe from a last having, in combination, a support for said last, a resilient member adapted frictionally to engage the rear portion of a shoe upper on said last, means including an eccentrically mounted tool rotatable to move said member into and out of operative engagement with said shoe, and means for holding said last support from being displaced by the pressure of said member during said engagement.

5. A machine for removing shoes from lasts having, in combination, a support for successive lasts having shoe uppers thereon, a slide on which said support is movably mounted, a gage limiting movement of shoes on said support to a predetermined position, and means including an eccentrically mounted tool rotatable to apply progressive pressure on said shoe uppers successively when the shoes occupy said position to effect relative movement between the shoes and their lasts.

6. A machine for operating on shoes comprising a friction mechanism, a driven eccentric roll included in said friction mechanism, a movable support for a lasted shoe, means for guiding the support to bring the rear of the shoe upper into a position for frictional engagement with said mechanism, and means for maintaining contact of said shoe upper with said mechanism whereby progressive pressure is imparted by said mechanism to move the shoe relatively to the last.

7. A machine for operating on shoes comprising an eccentrically mounted roll, means for driving said roll at a speed controllable at will, a support for a lasted shoe, said support being movable to and from an operating position, and an endless belt positioned adjacent to said roll and arranged, when pressed by said roll against a lasted shoe on said support while the support is in operating position, to partake of the traction of said roll and by frictional engagement with the shoe to move the shoe relatively to the last.

8. A machine for removing shoes from lasts comprising a rotatable driven eccentric roll, a shoe-engaging member positioned loosely to cooperate with said roll, a support for a lasted shoe, means for guiding the support toward and away from said shoe-engaging member, and means for locking the support in position whereby said member and the back portion of the shoe may be subjected to driving action imparted by the eccentric roll to move the rear portion of the shoe relatively to its last.
